MAGNETIC PICKUP UNIT FOR GUITARS

Gurnie E. Morrison, San Jose, Calif., assignor of
one-half to Robert Mickley, San Jose, Calif.

Application July 12, 1949, Serial No. 104,236

2 Claims. (Cl. 84—1.15)

1

This invention relates to electrically amplified metal stringed instruments and more particularly to an improved magnetic pick-up unit for such types of musical instruments.

Magnetic pick-up units in which vibrations of a string are imparted to an armature for the purpose of setting up a small voltage disturbance therein are not broadly new. The theory and electrical phenomena is well known in the art and has been adapted and employed in various applications.

The present invention has as its object to provide an improved magnetic pick-up unit which is simple in construction, inexpensive to manufacture and highly efficient in use.

Another object of this invention is to provide a pick-up unit having a separate bar magnet for each string of the musical instrument with which the pick-up unit is to be employed.

Yet another object is to provide a single compact unit with a plurality of individual and independent bar magnets each of which is disposed so that its magnetic field is influenced and affected by a corresponding individual string of the musical instrument.

These and other objects of the present invention will become more apparent from the following description when read in the light of the drawing in which:

Fig. 1 is a perspective view of a stringed instrument embodying the present invention.

Fig. 2 is a partial longitudinal section of Fig. 1 taken substantially along line 2—2 thereof.

Fig. 3 is a section taken along line 3—3 in Fig. 2 showing a portion of the instrument in elevation.

Fig. 4 is a cross section of Fig. 2 taken along line 4—4 thereof.

Fig. 5 is a horizontal section of the magnetic pick-up unit only as seen from line 5—5 in Fig. 4.

Fig. 6 is an exploded perspective view of the magnetic pick-up unit of the present invention; and

Fig. 7 is a schematic diagram illustrating the eddy currents of neighboring bar magnets of the pick-up unit as affected by the vibrations of adjacent strings of the musical instrument.

Referring now to the drawing, a stringed instrument, generally designated by reference numeral 10, comprises a neck 11 consisting of a continuous cast aluminum body upon which is secured a plastic fretted keyboard 12.

As shown in Figs. 1, 2 and 3, the neck 11 extends the full length of the instrument and is provided with a number of string-tightening keys 13 at one of its ends and at its opposite end with a flat panel 14 flush with the fretted keyboard 12.

The panel 14 is built up of a series of plates

2

of plastic material, two (15 and 16) of which are secured by plastic cement to the side edges 17 of the plastic fretted keyboard 12 flush with the upper surface 18 thereof. Two other plates 19 and 20 are cemented beneath plates 15 and 16 respectively and to the side edges 17 of the keyboard 12, and bottom plates 21 and 22 are cemented to the lower face of the plates 19 and 20 respectively and are each cut out as at 23 and 24 adjacent the neck 11 to provide a chamber 25 within the panel 14.

The gap which would ordinarily exist between lower plates 23 and 24 at the fore end of panel 14 is filled in by a strip of plastic material 26 and a sheet of pressed wood or some such suitable material is fastened by screws 27 to the bottom surfaces of these plates 23, 24 and 26 to enclose the chamber 25.

Referring now to Figs. 2, 3, and 4, it will be noted that the plates 15—16 and 19—20 are cut away to provide a rectangular shaped pocket 28. This pocket 28 is flanked on its two sides by up-standing walls 29 of plastic material and the pocket is adapted to receive the magnetic pick-up unit 30 of the present invention. The unit 30 comprises a coil portion 31 and a bridge block 32—the latter of which is provided with a groove 33 in which a bridge bar 34 is disposed. The block 32 has a central bore 35 through which the shank 36 of a wing bolt 37 extends for threaded connection to a tapped bore in the aluminum neck 11. A cover plate 38 rests upon the top edges of the side walls 29 of opening 28 and the winged head of the bolt 37 secures plate 38 in position in predetermined spaced relation with respect to the upper surface of the unit 30.

The heel end 39 of the neck 11 is provided with a plurality of transversely aligned holes 40 through each of which a particular string 41 of the instrument extends. The end of each string is suitably fastened to an anchor knob 42 and each string is stretched under cover plate 38 and over the bridge bar 34, lengthwise the fretted keyboard 12 and over a bridge plate 43 adjacent the string-tightening keys 13, each of which has the end of a respective string 41 wound about its extended binding post for controlling the taughtness and tonal value of the strings.

The coil portion 31 of the pick-up unit has a pair of lead wires extending from it and these leads are connected as shown in Fig. 3 to certain binding posts of potentiometers 45 and 46, each of which is grounded as at 47 to the aluminum spine or neck 11. Opposite terminals of the potentiometers are connected to a jack 48 adapted to receive a plug of an amplifier (not shown).

Each potentiometer 45 and 46 has a hand control knob 49 and 49' respectively associated therewith and disposed above the upper surface of the panel 14 in a position to be accessible to the

player of the instrument for changing the volume of sound emanating from the pick-up unit.

The magnetic pick-up unit 38 of the present invention, as best seen in Figs. 2 through 6, comprises a center core 50 of non-conductive material having a plurality of bores 51 formed therein corresponding in number to the number of strings 41 and spaced to coincide therewith. This core 50 is cemented at top and bottom to a top plate 52 and a bottom plate 53, respectively, each of which is provided with a plurality of holes, each aligning with and in registration with the respective bores 51 in the core. A very fine wire is wound around the core 50 about five thousand turns to comprise a coil 31' and the respective ends of this wire are the leads mentioned above as being connected to the potentiometers 45 and 46.

The coil 31' is closed in by cementing a front plate 54 and side plates 55 and 56 to each other and to the top and bottom 52-53 and thereafter the balance of the space surrounding the core and coil is filled with paraffin. The back of the paraffin filled coil portion is then closed by cementing the bridge block 32 to the top, bottom and side plates 52, 53, 55 and 56 so that the coil portion 31 and bridge block 32 become integral with each other.

Disposed in each bore 51 and adapted to extend through the holes registering with the bore is a permanent bar magnet 60. These bar magnets are of a length adapted to extend into respectively aligned holes 61 formed in the spine or neck 11 of the instrument. Each bar magnet 60 is held in place by a set-screw 62 threadedly associated with a tapped bore 63 extending from the bar magnet to the forward edge of the bottom plate 53. In this manner when the unit 30 is removed from the pocket 28 in the panel 14, the set-screws 62 can be manipulated and the bar magnets shifted within their respective bores 51 to dispose the upper ends of the magnets above or below the upper surface of top plate 52, i. e. close to or substantially spaced from the particular wire string 41 associated therewith.

Referring now to Fig. 7 wherein the eddy currents or fields of adjacent magnets are shown in phantom, it will be noted that the field of each magnet is confined to the particular space allotted it. That is to say, since the polarity of each bar magnet is the same, the magnetic forces thereof repel each other and are confined to space allotted each bar magnet. Moreover, it will be noted that the string 41 above each magnet lies within the field of its respective magnet 60 and since the strings 41 are of metal the field in which each string lies is correspondingly distorted due to the magnetic attraction of the field toward such string.

From the foregoing it will be understood that any motion of a string from side to side of the vertical center of its related bar magnet attracts the magnetic field thereof from side to side, setting up a disturbance in the winding of the induction coil 31'. In this connection it will be noted that only the field of the bar magnet related with a particular vibrating string is affected thereby and consequently the true tonal value of such string will not become discordant by reason of entrance of such string into the magnetic field of an adjacent bar magnet. Hence a clear tone is at all times assured.

It will be apparent to those skilled in the art that the device described herein is but one specific form and structural aspect of the invention which is susceptible to variations and modifications without departure from the spirit of the invention. I therefore desire to avail myself of all modifications, variations and alterations in structure coming within the purview of the appended claims.

10 What I claim as new and desire to protect by Letters Patent is:

1. In a pick-up unit for an electrically amplified metal stringed musical instrument comprising a core, an induction coil around said core, a top and bottom plate secured to said core, end walls secured to said top and bottom plates, a bridge block secured to the edges of said top and bottom plates and said end walls at one side thereof, a side wall secured to the edges of said top and bottom plates and the edges of said end walls on that side of the core opposite said bridge block, said core having a plurality of bores spaced from each other so as to register with the strings of said instrument and to be disposed with the axes of said bores perpendicular to said strings, a permanent bar magnet disposed in each of said bores with common poles of said bar magnets disposed in substantially the same plane as each other so that the magnetic forces of adjacent magnets repel each other to confine the magnetic field of each bar magnet to the laterally extending zone of each string of said instrument, and set-screws threadedly associated with said bottom plate and in alignment with each of said bar magnets for securing the latter in position vertically relative to said core and the strings of said instrument.

2. In a pick-up unit for an electrically amplified metal stringed musical instrument comprising a core, an induction coil around said core, a top and bottom plate secured to said core, end walls secured to said top and bottom plates, a bridge block secured to the edges of said top and bottom plates and said end walls at one side thereof, a side wall secured to the edges of said top and bottom plates and the edges of said end walls on that side of the core opposite said bridge block, said core having a plurality of bores spaced from each other so as to register with the strings of said instrument and to be disposed with the axes of said bores perpendicular to said strings, and a permanent bar magnet secured in each of said bores with common poles of said bar magnets disposed in substantially the same plane as each other so that the magnetic forces of adjacent magnets repel each other to confine the magnetic field of each bar magnet to the laterally extending zone of each string of said instrument.

60 GURNIE E. MORRISON.
